UNITED STATES PATENT OFFICE.

CHARLES J. SHIELDS, OF COLUMBUS, OHIO.

RAIL-CONNECTING CHAIR-PLATE PATTERN.

1,378,728.

Specification of Letters Patent. Patented May 17, 1921.

Application filed August 27, 1920. Serial No. 406,324.

To all whom it may concern:

Be it known that I, CHARLES J. SHIELDS, a citizen of the United States of America, residing at Columbus, in the county of 5 Franklin and State of Ohio, have invented certain new and useful Improvements in Rail-Connecting Chair-Plate Patterns, of which the following is a specification.

My present invention relates generally to 10 rail connecting chair plates, and more particularly to the manufacture of chair plates for use in spanning the joints between, and connecting in stepped relation, the adjacent ends of rails of different sizes, that is different heights, widths and thicknesses.

It is well known that but a simple matter is presented in the formation and utilization of patterns for casting chair plates to be used in the connection of rails of similar sizes, but dissimilar rails present a much 20 different, more complicated, expensive and troublesome situation as the rail chairs must properly fit the rails so that the latter are joined in stepped relation as to their bases 25 and offset relation as to their webs, with the inner side and top faces of their heads in alinement. This latter situation at the present time requires a skilled pattern maker and usually a different and newly made pattern for each different type of connection 30 encountered, and as the types of connections met with in practice are of widely varying natures, it is obvious that much difficulty and expense attends the ordinary solution of 35 the matter.

It is to avoid the necessity of making new patterns for castings for each type of offset or stepped joint at the junction of rails of different sizes, as well as to avoid the 40 necessity of the services of a skilled pattern maker, that my invention proposes and has for its object and construction whereby patterns may be formed by assembling standard sizes of rail end engaging sections 45 with detachable interchangeable connecting sections whose offsets will correspond to various combinations of end sections, and with base pieces whose stepped surfaces also correspond thereto and to the offset connecting sections and are likewise detachable and interchangeable.

In this way it will simply be necessary to maintain at hand the standard end sections of various sizes together with offset connecting sections for various combinations of end

sections, and base plates corresponding to the offset connecting sections, in order that a proper pattern for a particular offset joint or rail junction may be readily and quickly assembled without requiring any particular skill in this operation.

In the accompanying drawings illustrating my invention, and wherein for the purpose of better illustration and more ready understanding I have shown my improved 65 adjustable pattern in connection with rail ends to be connected, similar to the manner in which chair plates cast from the patterns will be actually used,

Figure 1 is a side view showing my improved pattern in connection with rails, 70

Fig. 2 is a top plan view thereof,

Fig. 3 is a horizontal section taken on line 3—3 of Fig. 1, but showing the actual chair plates as formed from the pattern constituting my invention, 75

Figs. 4, 5 and 6 are vertical transverse sections taken respectively on lines 4—4, 5—5 and 6—6 of Fig. 1,

Fig. 7 is an inner side view of one of the 80 patterns,

Fig. 8 is a top plan view thereof,

Fig. 9 is a vertical transverse section taken on line 9—9 of Fig. 3,

Fig. 10 is an enlarged inner side view of 85 the connecting section of the pattern,

Fig. 11 is an end view thereof, and

Fig. 12 is a top plan view thereof.

Referring now to these figures and particularly to Figs. 1 to 6 inclusive, my invention proposes a pattern for use in forming chair plates 15 shown more especially in Figs. 3 and 9, which are properly offset at points intermediate their ends to properly connect rails 16 and 17, of different 95 sizes, and whose bases 18 and 19 and webs 20 and 21 must be offset, the former vertically and the latter horizontally, in order to bring the inner side and upper surfaces of the rail heads 22 and 23 in alinement 100 as particularly seen by reference to Figs. 1 and 2.

The pattern as proposed by my invention and whose showing in Figs. 1, 2, 4, 5 and 6 at opposite sides of joint ends of the rails 105 16 and 17 is artificial, to the extent that the patterns are shown in these figures in place of the chair plates cast therefrom and actually utilized in practice, embodies detachable end sections 24 and 25, formed separate 110

from one another and in standard sizes to properly fit standard sizes of rails. Each of these sections, as particularly shown in Figs. 4 and 6, has a body properly shaped and formed of wood as indicated at 26, which is preferably bound with metal as at 27 in order to prevent warping and distortion under varying climatic conditions, as well as conditions of use, so that the necessity of re-fitting from time to time is avoided. Each standard section 24 and 25 has a flange portion 28 with vertical openings for the reception of screws 29, the latter of which serve to detachably connect the outer edges of the flanges upon the vertically offset or stepped surfaces 30 and 31 of the base plate 32 which forms a part of the pattern, it being understood that a variety of base plates will be provided having their surfaces vertically spaced to properly hold with the vertical spacing of the vertically offset rail bases.

With the standard sections 24 and 25 thus secured upon the base plate 32, the inner ends of these standard end sections, provided with vertical grooves 33 as shown in Fig. 12, are connected by offset connecting sections 34, preferably formed of wood and either bound or unbound, or formed of metal and further provided with vertical side ribs 35 to extend into the grooves 33 of the end sections. These connecting sections 34 have endwise projecting threaded studs 36 adapted to extend into socket portions at the inner ends of the end sections 24 and 25 as shown in Fig. 10 and to receive connecting nuts 37, so that the inner ends of the end sections 24 and 25 will thus be rigidly connected in their proper vertically and horizontally offset relation particularly seen by a comparison of Figs. 7 and 8.

By the means described I am thus enabled to provide for the ready formation of patterns by simply keeping in stock standard end sections 24 and 25 and interchangeable base plates 32 and interchangeable connecting sections 34 to accord with various combinations of end sections of different sizes so that in use it becomes simply a matter of measurement and selection of proper sections, the actual joining of these sections being obviously a simple operation which needs no skill as compared to that of a pattern maker which the present practice of making a single one-piece pattern for each chair plate requires.

It furthermore becomes obvious that my invention thus does away to a maximum extent with the disadvantages, trouble and expense in properly providing for the connection of adjoining ends of rails of different sizes, as well as delays incident to the making and fitting of new patterns.

I claim:

1. A pattern for the casting of interme-

dately offset rail connecting chair plates, including end rail engaging sections of standard sizes to fit standard rails, and interchangeable intermediate sections forming connecting members for the end sections having offsets to correspond with particular sizes of end sections, as described.

2. A pattern for the casting of intermediately offset rail connecting chair plates, including end rail engaging sections of standard sizes to fit any rails, and interchangeable intermediate sections forming connecting members for the end sections having offsets to correspond with particular sizes of end sections, each of said end sections including a body portion having a binding to prevent warping and distortion in use.

3. A pattern for the casting of intermediately offset rail connecting chair plates, including interchangeable end sections of standard sizes to fit all sizes of rails, a vertically and horizontally offset connecting member detachably connecting the inner ends of said sections, and whose offsets correspond to the dissimilar sizes of the end sections, and a base plate to which the end sections are detachably connected, having vertically offset upper surfaces corresponding to the vertical offset of the connecting member as described.

4. A pattern for the casting of intermediately offset rail connecting chair plates, including interchangeable end sections of standard sizes to fit various sizes of rails, a vertically and horizontally offset connecting member detachably connecting the inner ends of said sections, and whose offsets correspond to the dissimilar sizes of the end sections, and a base plate, said end sections and said connecting section having relatively engaging ribs and recesses to maintain the same in proper alinement.

5. A pattern for the casting of intermediately offset rail connecting chair plates, including interchangeable end sections of standard sizes to fit all sizes of rails, a vertically and horizontally offset connecting member detachably connecting the inner ends of said sections, and whose offsets correspond to the dissimilar sizes of the end sections, and a base plate, said end sections and said connecting section having relatively engaging ribs and recesses to maintain the same in proper alinement, the connecting section also having endwise projecting threaded studs adapted to enter sockets of the end sections, and nuts engaging the studs to secure the end and connecting sections together.

In testimony whereof I have affixed my signature.

CHARLES J. SHIELDS.
